United States Patent Office.

O. B. HALE, OF MALONE, NEW YORK.

Letters Patent No. 87,844, dated March 16, 1869.

IMPROVEMENT IN DEVICE FOR PULLING HOP-POLES.

The Schedule referred to in these Letters Patent and making part of the same.

To all whom it may concern:

Be it known that I, O. B. HALE, of Malone, in the county of Franklin, and State of New York, have invented a new and useful Device for Pulling Hop-Poles; and I do hereby declare that the following is a full, clear, and exact description thereof, which will enable others skilled in the art to make and use the same, reference being had to the accompanying drawings, forming part of this specification.

This invention relates to a new and improved device for the purpose of pulling hop-poles, and has for its object simplicity and economy in construction, together with facility in the manipulation of the device, and the withdrawing of the poles, without the necessity of shaking the same, and causing the hops to drop from the vines.

The accompanying drawing represents my invention applied to a person as when in use.

The device is constructed on the principle of a tongs, A A being two bars, or shanks, which cross each other, and are connected by a pivot-bolt, a, at one side of the centre of their length, so that the bolt a will be near the jaws B B, the latter being formed by bending A A, at one end, at right angles with the main portions, and corrugating the inner edges of the bent parts, or jaws B, to form teeth, b, as shown clearly in the drawing.

The bending of the bars, or shanks, to form the jaws B B, gives the tongs a considerable leverage-power.

The handles C C of the tongs are formed by forging

or drawing out the upper ends of the bars, or shanks, and bending them over, in loop-shape, at right angles with A A, as plainly shown in the drawing.

Each handle C of the device has a strap, D, attached to it, and these straps extend over the shoulders of the operator, and may be lengthened or shortened, by means of buckles, e, so that the device may be suspended, to suit the height of the operator.

If necessary or desired, a cross-strap, (shown in dotted lines,) may be attached to the shoulder-straps D D, to keep them in their proper place.

By this simple device, the hop-poles may be drawn or pulled out of the ground, without shaking them, and causing the hops to drop from the vines.

The shoulder-straps D D, it will be seen, enable the operator to apply the muscles of the legs, and other parts of the body, as well as those of the arms, to the prosecuting of the work.

Having thus described my invention,

I claim as new, and desire to secure by Letters Patent—

A device for pulling hop-poles, constructed and operated in the manner substantially as herein shown and described.

O. B. HALE.
